UNITED STATES PATENT OFFICE.

ANDREW BERG, OF BRIDGEPORT, CONNECTICUT, ASSIGNOR TO THE COULTER & MCKENZIE MACHINE COMPANY, OF BRIDGEPORT, CONNECTICUT.

ROTARY SWAGING MACHINE.

Application filed March 12, 1924. Serial No. 698,699.

To all whom it may concern:

Be it known that I, ANDREW BERG, citizen of the United States, residing at Bridgeport, in the county of Fairfield and State 5 of Connecticut, have invented certain new and useful Improvements in Rotary Swaging Machines; and I do hereby declare the following to be a full, clear, and exact description of the invention, such as will enable others skilled in the art to which it 10 pertains, to make and use the same.

My invention relates to machines of the type known as rotary swagers. The machines of this character, in common use, rotate the die carrying head against a series of rollers and are adapted only for circular swaging, whereas, in my improved type of machine, the die carrying head is held stationary, and the rollers are revolved about 15 the head so that articles of any irregular shape are capable of being forged by simply varying the shape of the dies to correspond to the shape of the finished product.

Referring to the drawings wherein the 20 same numerals of reference indicate like parts through the several views,

Figure 1 represents a side elevation of the machine;

Figure 2 is a detail view of the stationary 25 die carrying head and its shank, sectional view of the rotatable roller carrying head embracing the die carrying head, sectional driving gear rotatably mounted on the shank of the die carrying head and integral with 30 the roller carrying head;

Figure 3 is a detail view of the front face of the die carrying head;

Figure 4 is an enlarged front elevation 35 of the die carrying and roller carrying heads, and sectional view of the roller carrying head on line 4—4 of Figure 2;

Figure 5 is an enlarged detail view of a pair of swaging dies operating on a piece of work;

Figure 6 is a similar view of the swaging dies and finished work;

Figure 7 is an enlarged broken sectional view of the roll carrying head, and broken view of the die carrying head showing a 40 modified view of the means for normally expanding the die holding slides, and

Figure 8 is an enlarged broken sectional view of the rotating head showing a substitute for the rollers, and broken view of 45 the die head and one of the slides.

1 represents the machine bed or standard in which is journaled the driving shaft 2 carrying the tight pulley 3 and loose pulley 4. This shaft also carries the pinion 5 meshing with the large gear 6 rotatably mounted 60 on the enlarged portion 7 integral with the die carrying head 8. The reduced portion 7^a of said shank is firmly secured in the machine standard, Figure 1.

The large gear 6, Figure 2, forms an integral part of the roller carrying head 9 in which are journaled the rollers 10, Figures 2 and 4.

The head 8, Figure 3, is provided with the radial slots 11 adapted to receive the radially operating slides or carriers 12, 13, 14, and 15, Figure 4. 16, 17, 18, and 19, are the forging or swaging dies carried by the slides and are preferably detachable therefrom so that they can be interchanged to suit any 75 irregular shaped work required. The slides are held in place by the removable plate 8^a, Figure 1.

20 are recesses formed in one face of the slides 12, 13, 14, and 15, adapted to receive 80 the ends of the arms 21, 22, 23, and 24, of the levers 25, 26. These levers are operatively mounted in the recesses 25^a 26^a, Figure 3, of the die carrying head 8 and open into the slots 11. Springs 27 engage 85 the arms of the levers 25, 26, so as to maintain a uniform spring balance to the die carrying slides.

As the roller carrying head 9 rotates about the head 8, its rollers alternately contact with the slides to force them inward toward the work and bring their dies thereagainst. In Figure 4, it will be observed, the rollers 10 are temporarily engaged with the pair of opposed slides 12, 13, whose inward movement will actuate the levers 25, 26, to temporarily force outward the other two slides 14, 15, so as to give an unobstructed field for the operation of the slides 12, 13. When the rollers engage the slides 100 14, 15, the slides 12, 13, will in like manner be temporarily forced outward. This feature of forcing out the unemployed slides is convenient where small work is being operated upon, so as to give free play to 105 the operating slides. However, springs like, for instance, the spring 28, Figure 7, might be employed against each of the slides to exert a normal outward pressure, and in limiting the outward movement by the stop 110

pin 29. This arrangement would prevent the operative slides colliding with the temporarily inoperative slides.

As shown in the drawings, the dies employed are designed to form a taper tang, rectangular in cross section, and to form the tang at the end of the round rod 30. This rod is mounted in the V-shaped seats 31 of the carriage 32, Figure 1, with its outer end against the adjusting screw 33. The carriage is mounted on the support 34 secured to the die carrying head 8. The carriage is actuated to and from the dies by means of the handle lever 35, pinion 36, and rack 37. 38 is an adjustable stop screw adapted to limit the inward travel of the carriage.

The end of the rod is preferably heated to a degree suitable for swaging, and is gradually fed between the dies, see partially formed tang 39, Figures 1 and 5, until the complete taper tang 40 is formed, as shown in Figure 6. The number of rollers employed to actuate the dies will depend on the rotary speed of the head 9.

As before mentioned, the primary object and purpose of the present invention is to swage irregular shapes, and to accomplish this, it is absolutely essential that the die carrying head must remain stationary, while the means employed for actuating the dies to swage rotate about the die carrying head, which is the reverse, as before mentioned, of the operation for swaging articles round in cross section. I employ rollers for actuating the die carrying slides as greater speed and increased product is thereby obtained.

A pulley could be substituted for the gear 6, but it would not be as effective owing to its liability to slip. It is absolutely neces-

sary that the roller carrying head should rotate about the stationary die carrying head, and any suitable means to effect this would be considered an equivalent to the means employed.

It is evident that, the dies or operative tools and the slides could be made integral, but no economic advantage would be gained by doing so.

Projections similar to 9, Figure 8, could be substituted for rollers, but the rollers would show less friction and wear.

Having thus described my invention what I claim is:—

1. A machine of the character described, comprising a stationary head, a support for the head, radially operating die carrying slides mounted on the head, a rotatable roller carrying head embracing the stationary head, a support for the rotating head whose rollers are adapted to alternately engage each opposed pair of slides and temporarily force them inward, means connecting the pair of operating slides with the idle pair to retreat the latter when the former are advanced.

2. A swaging machine of the character described, comprising a supported head, radially operating die carrying slides mounted in the head and arranged in opposed pairs, means for alternately engaging each opposed pair and temporarily advance them toward the axis of the head, and pivotally supported levers under spring tension connecting the pairs of slides so that the advancing pair will retreat the other pair through the medium of said levers.

In testimony whereof I affix my signature.

ANDREW BERG.
